UNITED STATES PATENT OFFICE.

RICHARD P. PRENDERGAST, OF GALVESTON, TEXAS.

GARMENT.

954,132.

Specification of Letters Patent.

Patented Apr. 5, 1910.

Application filed November 16, 1909. Serial No. 528,332.

To all whom it may concern:

Be it known that I, RICHARD P. PRENDERGAST, a citizen of the United States of America, residing at Galveston, in the county 5 of Galveston and State of Texas, have invented certain new and useful Improvements in Garments, of which the following is a specification, reference being had therein to the accompanying drawing.

10 This invention relates to garment for wear by engineers, firemen and other persons whose occupations compel them to spend considerable of their time in abnormally heated places, and the principal object of 15 the same is to provide a garment for wear next to the body so that chafing of the limbs will be prevented.

In carrying out the objects of the invention generally stated above it will be understood, of course, that the essential features 20 of the same are necessarily susceptible of changes in details and structural arrangements, one preferred and practical embodiment of which is shown in the accompanying drawing, wherein:—

25 Figure 1 is a front perspective view of the improved garment. Fig. 2 is a rear perspective view thereof. Fig. 3 is a view in side elevation showing the practical use of 30 the garment.

Referring to said drawings by numerals, 1 designates the flat body belt whose ends may be fastened at the front by the buttons 2 or other suitable fasteners. At the rear the 35 belt is provided with two spaced apart eyeleted strips 3 which are adjustably connected by the lacing 4 so that the size of the belt may be varied.

Short leg portions 5 are provided for fitting 40 over the thighs of the wearer, said portions being connected to the belt 1 by the narrow length of material 6 which is a continuation of the outer side of said portions 5, and has its upper end stitched to the belt 1.

45 The inner end of the open upper part 6^a of each thigh portion 5 is connected by the short elastic strap 7, and the front and rear of said upper edge are connected to the belt by the vertically arranged elastic straps 8.

Each thigh portion 5 has its outer side 50 provided with a vertical slot 9 that extends from the lower edge thereof upward through the major portion of the garment, the vertical edges of said slot being connected by the regularly spaced apart horizontally arranged elastic straps 10.

It will be seen from the foregoing that the improved garment will protect the thighs of the wearer so that the same will not contact, thereby preventing the thighs being 60 chafed, such as is a common complaint with engineers, firemen and others who are employed in highly heated places. It will also be seen that the connecting and suspending straps employed being of elastic material, 65 they will readily yield to all movements of the wearer.

Preferably the improved garment is formed of light material, such as linen, and may be worn beneath the usual under-garments.

What I claim as my invention is:—

1. A garment of the class described comprising a body belt, thigh protectors having their outer side reduced and projected and 75 fastened to said belt, suspending means connecting the front and rear of said protectors to said belt and a connection between the inner upper end of each protector.

2. A garment of the class described comprising a body belt, thigh protectors having the upper portion of their outer side reduced and fastened to said belt and their lower portion provided with a vertical slot, elastic straps connecting the vertical edges of said 85 slot, elastic suspending straps connecting the front and rear upper edges of said protectors with said belt, and an elastic strap connection between the inner ends of the upper edge of said protectors.

90 In testimony whereof I hereunto affix my signature in presence of two witnesses.

RICHARD P. PRENDERGAST.
